UNITED STATES PATENT OFFICE.

JAMES VINCENT HUGHES, OF NEW FLORENCE, PENNSYLVANIA.

DESIGN FOR A LAMP GLOBE.

Application filed November 12, 1924. Serial No. 11,356. Term of patent 7 years.

To all whom it may concern:

Be it known that I, JAMES VINCENT HUGHES, residing at New Florence, in the county of Westmoreland and State of Pennsylvania, have invented a new, original, and ornamental Design for Lamp Globes, of which the following is a specification, reference being had to the accompanying drawing, forming part thereof.

The figure is an elevational view of a lamp globe, showing my new design.

I claim:

The ornamental design for a lamp globe, as shown.

JAMES VINCENT HUGHES.
